CLAMP FOR CONDUCTOR HARNESS OR THE LIKE

Raymond F. Piasecki, Hazlet, N.J., assignor to The Thomas & Betts Co., Elizabeth, N.J., a corporation of New Jersey

Filed Aug. 31, 1965, Ser. No. 86,783

Term of patent 14 years

(Cl. D54—1)

Fig. 1

Fig. 2

Fig. 3

FIGURE 1 is a perspective view of a clamp for conductor harness or the like in normal position showing my new design;

FIGURE 2 is a similar view of the clamp or support as seen from the rear side of FIGURE 1; and

FIGURE 3 is a perspective view of the clamp similar to FIGURE 1, but showing the clamp in closed position and as secured to an apertured panel shown in broken lines for illustrative purposes only.

I claim:

The ornamental design for a clamp for conductor harness or the like, as shown and described.
